[57] CLAIM

The ornamental design for an insulation panel dispensing bag, substantially as shown and described.

DESCRIPTION

FIG. 1 is a frontal perspective view of an insulation panel dispensing bag showing my new design.

FIG. 2 is a top plan view thereof.

FIG. 3 is a frontal elevational view thereof.

FIG. 4 is an elevational view thereof taken from the end as seen from the left of FIG. 3, the opposite end being a mirror image thereof.

FIG. 5 is a bottom plan view thereof.

FIG. 6 is a reduced in scale rear elevational view thereof.
